United States Patent Office.

WILLIAM RICHARD, OF CLYDE, OHIO.

Letters Patent No. 94,514, dated September 7, 1869.

IMPROVEMENT IN PRUNING-SHEARS.

The Schedule referred to in these Letters Patent and making part of the same.

To all whom it may concern:

Be it known that I, WILLIAM RICHARD, of Clyde, in the county of Sandusky, and State of Ohio, have invented certain new and useful Improvements in Pruning-Knives; and I do hereby declare that the following is a full, clear, and exact description thereof, reference being had to the accompanying drawings, and to the letters of reference marked thereon, which form a part of this specification, and in which is represented a plan view of my pruning-knife.

My invention relates to improvements in pruning-knives; and to this end,

It consists in the employment of convex and concave blades, operated by means of levers, substantially in the manner and for the purpose hereinafter described.

To enable others skilled in the art to which my invention appertains, to make and use the same, I will now describe its construction and operation.

In the accompanying drawing—

A represents a convex blade, and

B, a similar concave blade.

The blade A is formed, on its shoulder, with the slot C, through which is passed a pin, the lower end being secured to the blade B, as seen in the drawing.

D represents a lever, one end of which is attached to the blade B, and the other end attached or pivoted to the lower end of the blade A.

F and P are the handles, which are pivoted together near their centres, and each end pivoted to the lower ends of the blades A and B.

E represents a hook, formed on the blade A. This hook is made sharp on its lower side, and is used to cut off small branches.

By this arrangement of my pruning-knife, I gain four times more power than in any pruning-knife yet invented.

Having thus described my invention,

What I claim as new, and desire to secure by Letters Patent is—

The slotted blade A, pivoted to the blade B, and provided with hook E, in combination with lever D and handles P and F, substantially in the manner and for the purpose described.

In testimony that I claim the foregoing as my own, I affix my signature, in presence of two witnesses.

WILLIAM RICHARD.
